AIRPLANE

Edward M. Lanier, 900 Newportville Road, Croydon, Pa.

Filed May 15, 1959, Ser. No. 55,925

Term of patent 14 years

(Cl. D71—1)

Fig. 1.

Figure 1 is a plan view of an airplane showing my new design;

Figure 2 is a side elevational view thereof; and

Figure 3 is a front elevational view thereof.

The side of the airplane opposite that shown in Figure 2 is substantially the same in appearance aside from the door as the side shown in Figure 2.

I claim:

The ornamental design for airplane, substantially as shown and described.
